BY *D. C. Davis*

ATTORNEY

UNITED STATES PATENT OFFICE.

ERIC ZETTERQUIST, OF ESSINGTON, PENNSYLVANIA, ASSIGNOR TO WESTINGHOUSE ELECTRIC AND MANUFACTURING COMPANY, A CORPORATION OF PENNSYLVANIA.

EXHAUST TURBINE BLADING.

Application filed December 21, 1923. Serial No. 682,101.

My invention relates to elastic-fluid turbines and it has for an object to provide exhaust or low-pressure blading for apparatus of this character which shall be capable 5 of handling large volumes of low-pressure elastic fluid efficiently with little, if any, loss due to drop in pressure in the motive fluid as it passes between the blades.

More particularly, my invention relates 10 to wide blading of the lateral-receiving and peripheral-discharging type and it has for an object to provide blading of this character having energy-abtracting portions arranged at small angles and which allows for 15 change in direction of flow without necessitating an increase in area between the inlet and outlet side so as to avoid substantial drops in pressure between the blade elements.

20 Apparatus embodying features of my invention is illustrated in the accompanying drawing, forming a part of this application in which: Fig. 1 is a sectional detail view of a turbine showing my improved 25 low-pressure blading applied thereto; Fig. 2 is a section taken along the lines II—II of Fig. 1; Fig. 3 is a section taken along the line III—III of Fig. 1; Fig. 4 is a view similar to Fig. 1 but showing a modified arrangement of low-pressure blading; and 30 Fig. 5 is a perspective view of adjoining portions of a pair of low-pressure blade elements.

In my application, Serial No. 682,102 filed 35 December 21, 1923 and assigned to the Westinghouse Electric and Manufacturing Company, I have disclosed and claimed a type of moving exhaust blading wherein the blades are arranged to divide the steam for 40 discharge from a plurality of rows of energy-abtracting elements so that motive fluid passages between the blades may be provided which do not increase in area substantially from the inlet to the exit, thereby 45 avoiding losses, due to drop in pressure as the motive fluid passes between the blades. In other words, a multiple exhaust low-pressure moving blade construction is provided wherein the total passage area from 50 the inlet side towards the outlet side or

sides may be maintained equal to or be made less than the total inlet area.

In accordance with my present invention, the cellular blade construction set forth in my application aforesaid is employed but 55 the energy-abstracting elements are modified. Fixed guide vanes defining expansion passages are provided for directing motive fluid into the moving blade structure; and the moving blade structure is 60 provided with energy-abstracting elements of the impulse or impact type at both sides and at the tips, although the latter elements may be of the type set forth in my 65 said application.

In the patent of Alexander T. Kasley, No. 1,469,925, issued October 9, 1923, and assigned to the Westinghouse Electric and Manufacturing Company, there is disclosed and claimed wide blading having peripherally-discharging, energy-abtracting portions which are of the spoon-outline type. In accordance with my present invention, I propose also to use blading of this type which is immediately preceded by a moving row of impulse elements adapted to receive motive fluid discharged from expansion passages defined by a stationary row of guide vanes.

Referring now to the drawings for a more 80 detailed description of my invention, in Fig. 1, I show a turbine comprising a rotor 10 and a casing or cylinder 11 provided with blading of any suitable type followed by my improved low-pressure or exhaust stage 85 consisting of guide blades 12 defining expansion passages, carried by the casing, and wide blade structures 13, carried by the rotor.

The wide blade structures include im- 90 pulse blade elements or buckets 14 arranged to receive motor fluid discharged by the guide blades 12 and which contact with the blade elements 15, the latter contacting in groups of two at the tips, as shown in Fig. 95 3, to provide energy-abtracting portions 16 defining discharge passages 17, arranged at a small angle as indicated by the angle α in Fig. 3, for the motive fluid passing through inter-group spaces at 18, and to de- 100

fine cellular passages at 19. The low-pressure moving blade structure also includes impulse elements 20 which are adapted to cover the inter-group spaces 18 at the outside and which define discharge passages 21 arranged at a small angle as indicated by the angle β in Fig. 2 for said cellular passages 19.

The opposed faces of the plate or blade elements 15, which define the inter-group spaces 18, are provided with suitable deflector structure 22 to gradually change the direction of flow of motive fluid in the inter-group spaces 18 from an axial to a radial direction. Similarly, the opposed faces of blade elements 15, which define the spaces 19, are provided with suitable guide plates 23 to maintain the motive fluid in a straight path through the spaces 19.

The inactive spaces 24, formed by blade elements 15, impulse elements 20 and deflectors 22, constitute a special feature of this type of exhaust blade structure, inasmuch as they represent a corresponding amount of solid material which for the proper design of annular blade structures, not employing the cellular construction, would cause prohibitive stresses at high rotative speed.

From the foregoing, it will be apparent that I have provided a low-pressure turbine stage of the impulse type wherein the moving blade structure is of the cellular type, that is, it is provided with plate elements which define spaces communicating alternately with the peripheral and lateral energy-abtracting elements 16 and 20, respectively. Thus, all of the available pressure energy in the motive fluid is converted into velocity energy by the stationary blades 12 and, thereafter, this velocity energy is abstracted by the impulse or impact elements 14, 16, and 20. The impulse elements 14, the registering plate elements 15 at the forward sides of the inter-group spaces 18, and the elements 16, in effect, constitute single impulse blade elements, and impulse elements 14 together with plate elements 15, guide plates 23 and impulse elements 20 constitute, in effect, impulse blade elements for the motive fluid passing through the cellular spaces 19.

The cellular construction of the moving blade structure 13 makes it possible to provide a total exit area adjacent to the energy-abtracting portions 16 and 20 which is not greater than the discharge area of the impulse elements 14. In this way, losses due to drops in pressure between the plate or blade elements 15 are substantially avoided. Also, this construction permits, not only of the advantageous relation of areas pointed out, but also of ample discharge area for steam at small leaving angles.

In Figs. 4 and 5, I show a modified form

of exhaust blades 25 following the guide blades 26 adapted to expand and to discharge motive fluid at a proper angle for entry between the moving impulse or impact elements 27 at the entrance sides of the moving exhaust blade structures 25. The moving exhaust blade structure is furthermore comprised by blade elements having inner radial portions 28 which contact and register with the discharging sides of the impulse elements 27 and which are provided with outer curved or spoon-outline energy-abtracting portions 29, such as disclosed and claimed in the patent to Alexander T. Kásley aforesaid. Suitable guide members 30 are carried by the blade portions 28 to constitute guides or deflectors to change the direction of flow of motive fluid from an axial toward a radial direction for action upon the energy-abtracting portions 29.

It is to be understood that the energy-abtracting portions 16 and 20 in Figs. 1, 2 and 3 may be, in action, either predominantly impulse or reaction. It is essential, however, that the guide blades 12 of Fig. 1 shall expand the motive fluid so as to discharge it to the low-pressure moving blade structure at a high velocity and at a relatively low pressure. I, therefore, prefer that the energy-abtracting portions at the tips and at the outer sides of the low-pressure moving blade structure of Figs. 1, 2 and 3, shall be of the impulse type so that the motive fluid may be at the lowest practicable pressure when it is discharged by the fixed guide vanes; however, as already stated, the motive fluid may be discharged from the guide vanes with sufficient residual pressure so that further expansion may be carried on by reaction expansion passages defined by energy-abtracting portions arranged peripherally and laterally. The latter scheme is involved in the modification disclosed in Fig. 4, wherein the motive fluid has pressure energy changed into velocity energy by the guide vanes 26, but it is discharged from the latter at a sufficient pressure for further expansion by the peripherally-arranged, reaction, energy-abtracting portions 29.

From the foregoing, it will be apparent that I have devised a multiple-exhaust low-pressure blade structure, provided with passage areas arranged in such a manner as to avoid losses due to drop in pressure as the motive fluid passes from the lateral inlet side to the lateral and peripheral outlet sides of my blade structure, the available pressure energy of the motive fluid having been partly or wholly converted into velocity energy by a stationary row of blades or nozzles before the motive fluid enters the moving blade structure.

While I have shown my invention in but two forms, it will be obvious to those skilled in the art that it is not so limited, but is

susceptible of various other changes and modifications, without departing from the spirit thereof, and I desire, therefore, that only such limitations shall be placed thereupon as are imposed by the prior art or as are specifically set forth in the appended claims.

What I claim is:—

1. In a turbine, a low-pressure stage comprising a row of vanes defining expansion passages followed by a row of blades having impulse energy-abtracting portions at the inlet edges and tip or peripherally-discharging energy-abtracting portions.
2. In a turbine, a low-pressure stage comprising a row of vanes defining expansion passages followed by a moving blade structure having energy-abtracting portions at the inlet and at the tips.
3. In a turbine, a low-pressure stage comprising a row of stationary vanes followed by a cellular blade structure having energy-abtracting portions at the inlet side and defining passages which lead to peripheral and lateral energy-abtracting portions.
4. In a turbine, an exhaust blade structure comprising radially-arranged impulse blade elements followed by wide blade elements arranged adjacent thereto, adapted to receive motive fluid therefrom, and having peripherally-arranged energy-abtracting portions.
5. In a turbine, an exhaust blade structure having energy-abtracting portions of the impulse type at the sides and at the tips.
6. In a turbine, an exhaust blade structure having energy-abtracting portions of the impulse type at the inlet side and at the tips.
7. In a turbine, a row of radially-arranged impulse elements merging into a wide blade having peripherally-arranged energy-abtracting portions.
8. In a turbine, a row of stationary blades adapted to convert pressure energy into velocity energy followed by a row of impulse elements contacting with blade elements having energy-abtracting portions at the tips thereof.
9. In a turbine, a low-pressure stage comprising a row of fixed blades defining expansion passages followed by a moving-row blade construction which includes a row of impulse elements, a row of wide blade elements contacting with the impulse elements, said wide blade elements contacting at their tips in groups of two to define energy-abtracting portions for the motive fluid received in the inter-group spaces and to define cellular passages, and a row of elements for abstracting energy from the motive fluid flowing through said cellular passages.
10. In a turbine, a moving blade construction comprising impulse elements which merge into flat plate elements disposed sub-

stantially in axial planes and having alternating peripheral and lateral energy-abstracting portions for the motive fluid passing between the plate elements.

11. In a turbine, a low-pressure stage comprising a row of fixed vanes defining expansion passages followed by a row of impulse blade elements contacting with flat plate elements arranged substantially in axial planes and which contact at their tips to define alternating peripherally-open and closed spaces between the plate elements and to define energy-abtracting portions for the motive fluid passing in said peripherally-open spaces, and impulse elements to receive the motive fluid flowing through said peripherally-closed spaces.

12. In a turbine, a row of stationary blades, a row of impulse elements, rows of impulse elements following said first row of impulse elements, and means for conducting motive fluid from said first row of impulse elements to said latter rows of impulse elements.

13. In a turbine, the combination of a row of guide vanes defining expansion passages, a row of impulse elements, rows of impulse elements following said first row of impulse elements, and means for conducting motive fluid discharged from said first row of impulse elements alternately to said latter rows of impulse elements.

14. In a turbine, the combination of a row of stationary vanes, a row of energy-abtracting elements followed by two other rows of energy-abtracting elements and means for conducting motive fluid discharged by said first row of energy-abtracting elements alternately to said latter rows.

15. In a turbine, the combination of a row of fixed guide vanes defining expansion passages adapted to discharge motive fluid in an axial direction, a row of blade elements adapted to abstract energy from motive fluid flowing in an axial direction, peripherally and laterally-discharging energy-abtracting elements, and means for conducting motive fluid discharged from said blade elements alternately to the peripheral and lateral discharging energy-abstracting elements.

16. In a turbine, a row of stationary blades followed by a moving blade construction which comprises inlet impulse elements followed by elements which define alternately arranged energy-abtracting portions so that the total passage area between the energy-abtracting portions and the discharge side of said impulse elements may be maintained equal to or be made less than the total discharge area of said impulse elements, whereby velocity loss of the motive fluid due to drop in pressure in passing to said energy-abtracting portions is substantially avoided.

- 17. In a turbine, a row of blade elements having impulse portions at the inlet edges thereof and alternately-arranged peripheral and lateral energy-abstracting portions, whereby the latter portions may be designed for efficient operation and the sum of any two passage areas through the blade structure is equal to or less than the discharge

areas of said impulse portions to avoid velocity loss in the motive fluid passing to the peripheral and lateral energy-abstracting portions.

In testimony whereof, I have hereunto subscribed my name this 3rd day of December, 1923.

ERIC ZETTERQUIST.
